(57) **CLAIM**

The ornamental design for a ball point pen, as shown and described.

DESCRIPTION

FIG. 1 is a front elevational view of a ball point pen, showing my new design;

FIG. 2 is a rear elevational view thereof;

FIG. 3 is a side elevational view taken from the right side of FIG. 1, the left side elevational view being a mirror image thereof;

FIG. 4 is a top plan view thereof;

FIG. 5 is a bottom plan view thereof;

FIG. 6 is a perspective view thereof; and,

FIG. 7 is a right side view in an exploded condition.
